R. R. H. McGINNIS,
BANJO,
APPLICATION FILED JAN. 22, 1917.

Patented Sept. 2, 1919.

UNITED STATES PATENT OFFICE.

RICHARD R. H. McGINNIS, OF NEW YORK, N. Y.

BANJO.

1,314,823.

Specification of Letters Patent. Patented Sept. 2, 1919.

Application filed January 22, 1917. Serial No. 143,746.

To all whom it may concern:

Be it known that I, RICHARD R. H. McGINNIS, a citizen of the United States, and a resident of New York, county and State 5 of New York, have invented a certain new and useful Improvement in Banjos, of which the following is a full, clear, and exact specification.

In the present methods of making banjos 10 the head which is usually of untanned skin of an animal is susceptible of absorbing moisture from the air, and the moisture chiefly collects around the peripheral portion of the head with a tendency to spread 15 toward its center. When the head is charged with moisture the sound of the instrument is greatly impaired, and frequently the head must be removed for being re-stretched on the rim of the body as well as 20 being allowed to dry before the instrument can be properly tuned.

My invention has for its object primarily to overcome these objections by providing a simple and efficient device constructed so 25 that when applied to a banjo, an air space is formed at its marginal portion wherein the moisture absorbed by the head will tend to collect, in order to obviate deadening the sound of the instrument by spreading toward 30 the central part of the head, and in conjunction with the air space a resonance ring is employed for intensifying the sound of the instrument.

A practical embodiment of the invention 35 is represented in the accompanying drawing forming a part of this specification in which similar characters of reference indicate corresponding parts in all the views, and will then be pointed out in the claims at the end 40 of the description.

In the drawings, Figure 1 is a fragmentary view showing a top plan of the head and part of the finger board of a banjo with one form of device embodying my invention 45 applied thereto.

Fig. 2 is a top plan of the device.

Fig. 3 is an edge view, partly broken away, of the device, taken on the line III—III of Fig. 2, and

50 Fig. 4 is an enlarged fragmentary sectional view taken on the line IV—IV of Fig. 1.

The device has a body portion 10 which is 55 preferably in the form of a band, or annular wall of metal, and this band is of a dimension so as to removably fit snugly on

the rim 11 of the body 12 of a banjo, as 13, when applied exteriorly thereover. The band, or annular wall of the body portion 10 may be of a suitable height, and extending 60 interiorly of the band in proximity to its lower edge may be a bead, as 14, for engaging a groove 15 provided in the rim 11 of the banjo to detachably fasten the device thereon.

In constructing the device I preferably turn the upper portion of the band 10 inwardly and then downwardly to form an inner reinforcing annular strip, as 16, which is soldered to the band and this strip is then 70 bent angularly inward of the band to provide an annular member or flat ring 17, and this annular member is of a width so that its second edge extends some distance inwardly of the band 10. By this formation 75 of the annular member 17 it is arranged a distance below the upper edge of the band 10 and the free edge of the annular member may be curved upwardly, as at 19.

Mounted in the curved edge of the annular member 17 is a resonance ring 20 serving 80 to intensify the tone of the instrument. This resonance ring is preferably made of a steel of a diameter so that its top is on a longitudinal plane some distance above the upper edge of the band 10, and the resonance ring is held in a stationary position on the annular member 17 by being soldered or otherwise secured thereto. Moreover, the resonance ring is of sufficient diameter so 85 that its greater part will be free of contact with other parts of the device, and when the head, as 21, which is usually of untanned skin of an animal, is applied on the rim 11 of the banjo the head is stretched over the 90 resonance ring. The edge part of the head is wrapped on a flesh hoop, as 22, in the usual manner, and this hoop is guided over the body portion, or band 10 of the device. A bail ring, as 23, is also disposed over the 95 head 21 and over the band 10 of the device so as to bear upon the flesh hoop, and by the employment of clamps, as 24, on the rim 11 of the instrument to engage the bail ring 23 the head 21 will be properly fitted on the 100 body or band 10. The flesh hoop 22, bail ring 23 and the clamps 24 may be of the usual, or any preferred forms, and do not 105 comprise a part of this invention.

By applying the head 21 over the resonance ring 20 and over the upper edge of the band 10 of the device, the air space 18 is 110

provided and the marginal edge part of the head will be on an incline relative to the central part of the head so that moisture when absorbed by the head will tend to spread toward the inclined part over the air space instead of spreading toward the center of the head.

In the foregoing description, I have embodied the preferred form of my invention, but I do not wish to be understood as limiting myself thereto as I am aware that modifications may be made therein without departing from the principle, or sacrificing any of the advantages of this invention, therefore I reserve to myself the right to make such changes as fairly fall within the scope thereof.

Having thus described my invention, I claim as new and desire to secure by Letters Patent:—

1. The combination with the rim, head and bail ring of a banjo, of a band between the rim and said ring having the head stretched over its upper edge, an annular member extending angularly inward of the

band and spaced underneath the head, and a resonance ring on the annular member in spaced relation to the band as well as contacting with the head to provide an air space around and under the marginal portion of the head, besides disposing the marginal portion of the head on an incline.

2. The combination with the rim, head and bail ring of a banjo, of a band between the rim and said ring, having the head stretched over its upper edge, and the upper edge part being bent downwardly, then bent right angularly inward of the ring and the free edge part of the right angular portion being curved upwardly toward the head, and a metallic ring in said curved portion of the band arranged in contact with the underside of the head as well as disposing the marginal portion of the head on an incline.

This specification signed and witnessed this 20th day of January A. D. 1917.

RICHARD R. H. McGINNIS.
